UNITED STATES PATENT OFFICE.

LESLIE E. KEELEY, OF DWIGHT, ILLINOIS.

DESIGN FOR A BOTTLE.

SPECIFICATION forming part of Design No. 12,187, dated March 15, 1881.

Application filed June 21, 1880. Term of patent 14 years.

To all whom it may concern:

Be it known that I, LESLIE E. KEELEY, a citizen of the United States, residing at Dwight, in the county of Livingston and State of Illinois, have invented and produced a new and original Design for Bottles, of which the following is a specification, reference being had to the accompanying drawings, forming part thereof.

10 Figure 1 is a sectional view of my newly-designed bottle; Fig. 2, a rear elevation, and Fig. 3 a front elevation, of the same.

15 My newly-designed bottle has for its object to call attention to the same by reason of its novel configuration, the body of the bottle being composed of four unequal sides—viz., a broad rectangular back, arranged at right angles to a narrow straight side, the opposite side and the front of the bottle being formed of unequal curves, and the neck of the bottle presenting four unequal tapering sections, terminating in a cylindrical mouth provided with an overlapping lip or spout.

20 B is the broad rectangular back, arranged at right angles to the narrow side, the front A and opposite side being formed of unequal curves, as shown. The four unequal sides com-

posing the body of the bottle are provided with four unequal tapering sections, C, forming the neck portion of the bottle, and which 30 terminates in a cylindrical mouth, a, having an overlapping lip or spout, as shown.

35 I am aware that a design for a bottle composed of two equal straight sides arranged at right angles to each other and provided with a circular front is not new, such being shown in the patent granted to W. H. Richardson under date of January 27, 1874, and numbered 146,783, and I do not therefore desire to claim such a construction; but

40 What I do claim is—

45 The design for a bottle herein shown and described, the same consisting of a broad rectangular back, B, arranged at right angles to the narrow side, the front A and opposite side being formed of unequal curves, and the neck portion C of the bottle being composed of four unequal tapering sections, terminating in a cylindrical mouth, a, substantially as specified.

LESLIE E. KEELEY.
